The ornamental design for an open top trash can, as shown and described.

DESCRIPTION

FIG. 1 is an isometric view of my new design for an open top trash can, as shown.

FIG. 2 is a top plan view of the invention.

FIG. 3 is a rear elevational view of the invention.

FIG. 4 is a left side elevational view of the invention.

FIG. 5 is a front elevational view of the invention.

FIG. 6 is a bottom plan view of the invention; and,

FIG. 7 is a right side elevational view of the invention.

The broken lines in the drawings represent portions of the open top trash can that are for illustrative purposes only and do not form a part of the claimed design.
